UNITED STATES PATENT OFFICE.

EVAN L. REED, OF STERLING, ILLINOIS.

RACK FOR GLASS GLOBES.

1,389,984.

Specification of Letters Patent. Patented Sept. 6, 1921.

Application filed July 18, 1919. Serial No. 311,705.

To all whom it may concern:

Be it known that I, EVAN L. REED, a citizen of the United States, residing at Sterling, in the county of Whiteside and State of Illinois, have invented certain new and useful Improvements in Racks for Glass Globes, of which the following is a specification.

My invention has reference to racks for glass globes, and has for its purpose to provide a simple and efficient support for receptacles of the kind mentioned, more specially for use in the home, for holding teas, spices and similar kitchen articles. By the use thereof it is possible to have the contents of the jars always in sight, and in position to be readily reached, when it is desired to remove the contents of any of the jars. In one form it is also constructed so as to be reduced to a compact space for the purposes of shipment or storage. It is not limited to the domestic use referred to above, but can be utilized for the display and sale of pickles, olives, preserves, candies, and other commodities in a sales-room. By the use of said device it is possible to arrange and group the various articles in an attractive manner, and so as to occupy a minimum of space.

The glass globes are also held in place conveniently for removing the same, when it is desired to replenish the contents thereof.

In the drawings:

Figure 1 shows my invention in front elevation, in position when in use. Fig. 2 is a detail of one of the holders 9. Fig. 3 is a cross-section of the frame of my device, with a part of the arms 9 broken away. Fig. 4 is a similar view, with some of the parts in a folded position. Fig. 5 shows a modified form of the device, in vertical cross-section. Fig. 6 is a horizontal cross-section, showing one of the retaining frames of the modified form of the device.

My invention comprises a rectangular frame, formed of end-pieces 1, at top bar 2, and a lower bar 3, all rigidly united at their ends. Pivoted to the pieces 1 is a pair of arms 4, with the outer ends of which is connected a bar 5, preferably in an integral manner. Said arms and bar are supported in a horizontal position, when in use, by means of a pair of braces 6, pivoted to the frame at their upper ends, and secured to the arms 4 by means of bolts 7. The frame is adapted for support against a wall by means

of perforated metal straps 8 fixed to the bar 2.

Secured to the bar 2 at regular intervals are pairs of spring arms 9, adapted to embrace the neck of a glass globe, as shown at 10, the bottom of said globe resting upon the bar 5. Any number of the globes can thus be held removably in place, in a convenient position for getting at the contents. This can be done by removing the top 11, which is provided with a knob 12 for that purpose. When removed from the jar the top can be supported in one of a pair of spring clips 13, fixed to the bar 5. Said bar is also provided with several pairs of clips 14, slidable thereon, the several pairs thereof being designed to hold labels 15 for indicating the character of the contents of the jars.

The bars 5 pass beneath the globes at a point a little in front of the center of gravity of said globes, so that the tendency of the globe is to incline in a rearward direction, toward the bar 2. This obviates the danger of the globe accidentally tipping forwardly and slipping out of the arms 9, which might be caused by the weight of the jar and its contents. By using a simple form of bar for the support of the globes the amount of material required for that purpose is reduced to a minimum.

When it is desired to ship or store the frames the bolts 7 are removed and the braces 6 and arms 4 folded into approximate alignment with the main part of the frame, as shown in Fig. 4. A number of the frames can be nested, or packed tightly together.

The structure above described comprises one unit of my invention. Several of said units can be arranged in cabinet form, if desired, the sizes of the units and of the jars supported therein being varied, so as to provide for more bulky articles, or for those requiring less space.

In Figs. 5 and 6 is shown another form of my invention, which is intended to be supported upon the floor of a room, instead of against the wall. It comprises a base, formed of a pair of cross-pieces 20, upon which is supported a pair of uprights 21, united at their upper ends by a plate 22, forming a shelf. Projecting inwardly from the uprights 21 are flanges 23, united at intervals by bars 24, each of which is adapted for the support of two or more of the glass

gloves 25, depending upon the length of such bars.

The globes 25 are held in place by means of cross-frames, having semi-circular portions 27, connected with the flanges 21 by means of end-pieces 28 and bolts 29 passing through the end-pieces and flanges, and provided with wing-nuts on their threaded ends. The parts 27 are united by a bar 30, integral therewith, and are braced by means of a bar 31, connected with said parts at its ends. Bails 32, preferably formed of wire, are hung on the bar 30 by means of loops on the ends of said bails, the other ends thereof being also looped to receive the bolts 29, by which means said bails can be held in closed positions. When thus closed the members 27 and bails 32 loosely embrace the necks of the globes 25, as indicated in broken lines at 33, and hold the same firmly from release. The contents of the globes can then be removed at will.

When it is desired to remove the jars themselves, the wing-nuts on the bolts 29 are released, and the bails swung out of the way.

To facilitate the movement of the device upon the floor, the cross-bars 20 are pro-

vided with rollers 26. The bars 24 may be provided with pairs of arms 34, similar to 30 the clips 13, for supporting the covers of the globes when they are removed.

It will be obvious that by reason of the globes being arranged in rows, one above the other, a comparatively small amount of floor 35 space is required for the invention.

What I claim and desire to secure, is:

1. A device of the class described, comprising a frame; a bar foldably connected with said frame, adapted to hold a plurality 40 of globes; braces foldably connected with said frame and detachably connected with said bar; and means for removably embracing the necks of said globes.

2. A device of the class described, comprising a suitably supported frame; a bar supported at a suitable distance in front of said frame, adapted to hold a plurality of glass globes; spring arms projecting from said frame at a suitable distance above said 50 bar, adapted to embrace the necks of said globes; and pairs of clips slideable on said bars, for holding labels indicating the character of the contents of the several jars.

In testimony whereof I affix my signature. 55
EVAN L. REED.
